FIG. 3

FIG. 4

INVENTOR

Harold Gordon Chute

UNITED STATES PATENT OFFICE

2,008,201

PACK CARRIER

Harold Gordon Chute, Seattle, Wash.

Application June 13, 1932, Serial No. 616,922

5 Claims. (Cl. 224—11)

The invention relates to that class of pack carriers or frames consisting of a frame of rigid material with a harness attached of flexible material. The object of the invention is to provide

- 5 a device of this class having a harness provided with means of adjusting the several parts thereof so that the straps may be adjusted in length and position and adjusted in such relation to each other as to suit the requirements of the user, and
 10 to provide means of carrying a pack upon the back by a device which will transmit the load to the chest, sides and to the lower part of the back and to the waist line and hips, and to prevent and do away with backward strain and
 15 downward strain upon a person's back and shoulders, and in which the straps and harness are so adjustable as to afford means of placing the weight of the load upon the hips, back, shoulders, or chest, or of distributing the weight of the load over the person's hips, back, shoulders, and chest simultaneously, or as desired by the user.

Another object of the invention is to provide a means of carrying a pack upon the back in which the straps are provided with means for adjusting the length thereof so that the straps may be adjusted, and adjusted in such relation to each other, as to conform to the size and dimensions and contour and shape of the user, and so that all stretch, give, and slack may be taken up, and so the pack and frame is kept clear and away from a person's body, and so that a space is provided between the pack and person affording air circulation therethru, and so that the straps lie snugly upon and against the user's body.

35 Another object of the invention is to provide means for carrying a pack upon the back so that the carrier and pack will be held rigid and not swing or slip or slide upward or downward or sideways or change its position upon a person's back, and in which the straps and particularly the shoulder straps are held so that they will remain in place and not swing, slide, slip, or move backward or forward, or from side to side, or otherwise.

45 Another object of the invention is to provide a pack carrier provided with means whereby the straps thereof may be easily and readily removed and replaced.

50 And still another object of the invention is to provide a pack carrier of simple and economical construction, and to provide a comfortable means of carrying a pack upon the back.

Other features and advantages of the invention will appear from the following description and specification of which the accompanying draw-

ing forms a part, in which the separate parts of my improvement are designated by suitable reference characters in each of the views, and in which:—

Figure 1 is a view showing the device in position upon a man's back.

Figure 2 is a front view of the device.

Figure 3 is a side elevation of the device.

Figure 4 is a detached fragmentary view of a part of the frame and a plate attached thereto.

Figure 5 is a fragmentary sectional view substantially on broken line 5—5 of Figure 3.

This invention is in the nature of an improvement on the pack carrier disclosed in my prior Patent No. 1,761,426, issued Jan. 30, 1930, and in a general way the present invention consists in providing a slideable and adjustable connection between two main shoulder straps and a rigid pack-supporting frame at the location where said shoulder straps are crossed at the back of the user; and in providing an adjustable connection between the upper ends of two side members of the pack-supporting frame and the front portions of the two main shoulder straps; and in providing an adjustable waistband in connection with a substantially semi-circular base member of the pack-supporting frame, said three adjustable connecting means cooperating with each other in such a manner as to make it possible to balance, distribute, and equalize loads and pressures in a manner which cannot be attained in practice by the use of fixed connecting means.

It is desirable that a pack carrier of this type should be adjustable to the individual user, and should also be adjustable to obtain a proper balance for loads of different weight and bulk and should further be adjustable to compensate for stretching or shrinkage in the harness portion of the pack carrier, said harness portion being made of flexible material as of cotton or leather straps which may change their length under a load when they become wet or dry out. The present invention takes care of all of the difficulties above pointed out.

Referring to the drawing I show a pack carrier embodying a relatively rigid pack supporting frame and a suitable harness for mounting said pack supporting frame on the body of a person in such a manner that when a load is secured to the pack supporting frame said load will be properly balanced and will be supported in the most advantageous way on the body of the person.

The pack supporting frame is preferably formed of tubular metal and may comprise two spaced apart upright tubular side pieces 4 and 5

which are rigidly secured together by tubular cross members 6 and 7 and by a tubular curved base member 8. The side members 4 and 5 may be curved to conform somewhat to the curvature of the body and the upper ends of said side members are curved forwardly to afford portions 22 which extend over the shoulders of the user. Loop or ring members 3 are secured to the ends of the curved portions 22. The base member 8 of the pack supporting frame is curved to substantially a semi-circular shape so as to extend around the waist of the user and the ends of said base member 8 are fixedly secured to plate elements 9. These plate elements 9 are positioned at the sides of the user of the pack carrier and may be curved, as shown in Figure 5, to conform to the curvature of the body. A slot 29 is provided in the rearwardly extending end of each plate element 9 for purposes hereinafter described.

20 The harness portion of the pack carrier is constructed so that it will comfortably fit the back and chest and waist and hips of a wearer and said harness portion is arranged so that it will always support the rigid parts of the frame clear of the body. This harness portion preferably consists of a waistband having a wider inner portion 19, which extends around the back of the user at the location of the waist or hips and is passed thru the slots 29 in the plate elements 9, and an outer portion which terminates in two narrower ends 30 which are adjustably connected with each other by buckle means 31. This makes the waistband formed by parts 19 and 30 adjustable as to length. By adjusting the length of this waistband it will be apparent that the bottom member 8 of the pack-supporting frame can be positioned closer to or farther away from the user's back and in this way the center of gravity of any load which is secured to the pack supporting frame may be varied to secure the most comfortable and least fatiguing distribution of the load.

30 The harness portion of the pack carrier also embodies two main shoulder straps 12 and 13 which rest on the shoulders of the user and are crossed in the back after the fashion common to a pair of suspenders and which extend from the back around to the sides and have their lower ends secured preferably by removable means, as by suitable bolts, see Figure 5, to the respective side plates 9. The front sides of the main shoulder straps 12 and 13 extend downwardly from the shoulders over the chest of the user and are adjustably and detachably connected, as by buckle means 17, strap means 15—16 and snap means 18 with rings 10 which are secured by fastening means 11 to the side plates 9. This provides for adjustment as to length and for quick attachment and detachment of the shoulder straps.

40 The rear portions of the main shoulder straps 12 and 13 are crossed just forwardly of the horizontal frame bar 6 and are loosely connected with said frame bar 6 by adjustable tie straps 24 being crossed at the rear of the frame bar 6. This affords a slidable and an adjustable connection between the main shoulder straps 12 and 13 and the rear portion of the frame, the slidable feature permitting a stretching or shrinkage of the main shoulder straps without drawing said shoulder straps out of their proper position and the

50 adjustable feature permitting the pack supporting frame, including the frame bar 6 to be moved outwardly away from the back of the user without exerting an outward pull on the shoulder straps, when the pack supporting frame is adjusted by varying the length of waistband 19 to properly

balance up a pack. This permits the shoulder straps always to lie snugly against the back. Buckle means 25 may be used to detachably connect the straps 24 to the straps 12 and 13.

The front portions of the main shoulder straps 12 and 13 are adjustably connected with the rings 3 at the upper ends of the pack supporting frame, as by straps 20, buckle means 26, and straps 27. This affords an adjustment by which the curved upper ends 22 of the pack frame bars 4 and 5 may always be kept clear of the shoulders of the user irrespective of changes in length of the main shoulder straps. Rivets 21 may secure the straps 20 to the main shoulder straps 12 and 13.

The rear loops of the rings 3 afford convenient means to which the upper portion of a pack or a sack or a load of any form, not shown, may be attached and other rings 3' are connected by straps 28 with the side plates 9 to afford securing means for the lower portion of the pack or load.

In the use of this pack carrier the same is placed upon a wearer in the position shown in Figure 1, with the main shoulder straps 12 and 13 fitting closely to the back, shoulders and chest and the waistband 19 extending across the back and resting on the hips. The front portions of the shoulder straps including the parts 16, 18, 16, 17, 26, 28 and 27 are preferably adjusted so that there is not much slack between the rings 3 and the rings 19, thus causing the said front strap portions to draw tightly against the chest when there is a load on the pack carrier. This relieves the shoulders and back of weight and pressure.

When the device is in use the weight of the pack or load will be supported chiefly by the waistband 19 and main shoulder straps 12 and 13 and any tendency of the upper portion of the load to tilt rearwardly will be borne as a pressure on the chest thru the connections with the front portions of the main shoulder straps. The upper curved portions 22 of the pack frame are not allowed to rest on the user's shoulders. If the main shoulder straps 12 and 13 stretch enough to permit the frame ends 22 to touch the shoulders said shoulder straps may be shortened by first loosening the straps 20 in buckles 26 and then tightening up the straps 15 and 16 in the buckle members 17, thus elevating the frame ends 22. When an adjustment of this nature is made the straps 20 are preferably adjusted to maintain the desired tightness of the front portions of the main shoulder straps. These two adjusting means thus cooperate with each other to maintain a desired relation between the several parts of the pack carrier. Adjustments of this nature are frequently desirable when the straps become wet or when they dry out after having been wet.

The slidable connection between the frame bar 6 and the crossed shoulder straps 12 and 13 allows automatic adjustment at this point in response to take up or stretching of the several straps and in response to adjustments of the nature described in the preceding paragraph. The adjustable feature of the straps 24 has a cooperation with the adjustable waistband and makes it possible to move the pack frame farther away from the back without pulling the straps 12 and 13 outwardly away from the back.

Adjustment of the waistband 19 may be desirable for the purpose of balancing up a load so that the center of gravity of the load may be caused to fall in the best possible location and any tendency of the upper portion of the load to tilt rearwardly may be overcome. Tightening of the waistband 19—30 will obviously cause the

lower end of the pack frame to stand away from the back of the user. By adjustment of the shoulder straps 12 and 13 it is possible to vary the relative proportion of weight which will be carried on said shoulder straps and on the waistband.

Members 4 and 5 and cross members 6 and 7 should not be in contact with the user's body. Should the waistband 19 or the main shoulder straps 12 and 13, or both, stretch enough to permit the said rigid members to touch the wearer's back the waistband 19 and the main shoulder straps 12 and 13 may be shortened by the adjustment means provided thus positioning the said rigid members away from the user's body. This adjustment of said waistband and shoulder straps may be made in such relation to each other as not to vary the relative proportion of the weight of the load which will be carried on said shoulder straps and on the waistband.

The several straps are readily removable and may be easily replaced.

Having described my invention what I claim is:

1. In a pack carrier of the class described, a harness adapted to be placed on the body of a person, said harness having two main shoulder straps crossed at the back, a substantially rigid pack frame connected with said harness, said pack frame having a substantially rigid cross bar extending over the crossed portions of said main shoulder straps, and two tie straps connected at spaced apart points with said two main shoulder straps and extending loosely over said cross bar on the side of the cross bar opposite from the main shoulder straps allowing said cross bar to occupy a position in spaced relation to said main shoulder straps clear of the back of a wearer and allowing relative movement between the shoulder straps and the cross bar.

2. In a pack carrier of the class described, a pack frame embodying two side bars connected together by substantially rigid cross bars and having a substantially semi-circular base member secured thereto; a flexible waistband connected with the forward end portions of said semi-circular base member and positioned within said base member in spaced relation from the base member in normal operation and arranged to engage with the back of a person at the location of the waist, means for adjusting the length of said waist band whereby the distance of said pack frame from the back of a person may be varied, two main shoulder straps connected with the ends of said pack frame base member and adapted to extend over the shoulders of a person, said main shoulder straps being crossed at the back, the crossed portions of said straps being positioned under one of said cross bars and resting against the wearer's back, two tie straps connected at spaced apart intervals with said two main shoulder straps and extending over said cross bar and means for adjusting the length of said tie straps.

3. In a pack carrier for the use of a person, a pack frame embodying two side bars having curved portions adapted to extend up over the shoulders of a person to a point near the front of the body, a base portion of substantially semi-circular shape secured to said side bars, two main shoulder straps having their lower

rear ends connected respectively with the ends of said semicircular base portion and extending upwardly in crossed relation and thence forwardly and thence downwardly and having their lower forward ends connected respectively with the ends of said semicircular base, other strap members having their upper ends connected with the forward ends of the side frame members and having their lower ends connected with the front portions of said shoulder straps at a substantial distance below the ends of said side frame members, and means for adjusting the length of said last named strap members to thereby vary the relative slackness between the front portions and the shoulder and rear portions of said main shoulder straps.

4. In a pack carrier for the use of a person, a pack frame embodying two side bars having curved portions adapted to extend up over the shoulders of a person to a point near the front of the body, a base portion of substantially semicircular shape secured to said side bars, two main shoulder straps having their lower rear ends connected respectively with the ends of said semicircular base portion and extending upwardly in crossed relation and thence forwardly and thence downwardly, adjustable means connecting the forward ends of said main shoulder straps with the respective ends of said semicircular base portion, other strap members having their upper ends connected with the forward ends of the side frame members and having their lower ends connected with the front portions of said main shoulder straps at a substantial distance below the ends of said side frame members, and means for adjusting the lengths of said other strap members.

5. In a pack carrier for the use of a person, a pack frame embodying two side bars having curved top portions extending upwardly and forwardly, a base portion of substantially semicircular shape secured to the lower ends of said side bars, a cross bar extending between said two side bars, side plates secured to the respective ends of said semicircular base portion, a flexible waistband connected with said side plates and extending across said base member on the concave side thereof, means for adjusting the length of said waistband, two main shoulder straps having their lower rear ends connected with the respective side plates and extending upwardly in crossed relation and thence forwardly and thence downwardly, two tie straps of adjustable length connected at spaced apart intervals with the back portions of said two shoulder straps and extending over said cross bar of said pack frame whereby said shoulder straps are loosely connected with said cross bar, adjustable means connecting the forward ends of said shoulder straps with the respective side plates, other strap members having their upper ends connected with the forward ends of the side frame members and having their lower ends connected with the front portions of said shoulder straps at a substantial distance below the ends of said side frame members and means for adjusting the length of said other strap members.

HAROLD GORDON CHUTE.
